UNITED STATES PATENT OFFICE.

OLIVER H. ORENDOFF, OF EUREKA SPRINGS, ARKANSAS.

MAILING-PACKAGE.

1,184,202.

Specification of Letters Patent.

Patented May 23, 1916.

Application filed May 13, 1915. Serial No. 27,902.

To all whom it may concern:

Be it known that I, OLIVER H. ORENDOFF, a citizen of the United States, residing at Eureka Springs, in the county of Carroll and State of Arkansas, have invented certain new and useful Improvements in Mailing-Packages, of which the following is a specification.

This invention relates to an improved mailing package which is intended to be used principally for sending third class and other matters through the mail which must be contained in a package easily opened and the principal object of the invention is to provide improved means for tying the package and to so construct this device that the buttons about which the tying cord is passed may serve to hold the address cards in place and may be adjusted to accommodate themselves to the size of the cards.

Another object of the invention is to so construct this device that the tying cord will be securely held in place thus preventing the package from accidentally coming undone but at the same time permitting the package to be opened for inspection by the post office authorities.

This invention is illustrated in the accompanying drawings, wherein:—

Figure 1 is a perspective view showing the device in use. Fig. 2 is a longitudinal sectional view through the mailing package. Fig. 3 is a view showing the element of one of the fasteners before being applied to the envelop and also as they appear after being applied to the envelop. Fig. 4 is a view of the envelop with the fastening buttons removed.

The envelop 10 is provided with the usual end and side flaps 11 and is provided with the slots 12, 13, 14 and 15 arranged as shown in Fig. 4 so that the buttons to be herein-after mentioned may be moved toward the center of the envelop or toward the edges thereof in order to engage the address card 16 and securely hold the same in place. These buttons designated in general by the numerals 17, 18, 19 and 20 are mounted in the slots of the envelops as shown in Fig.

2 and from an inspection of Fig. 3 it will be readily seen that each of these buttons comprises the inner and outer disks 21 and 22 which are connected by the pin or fastener 23. The pin 23 shown in this drawing is of the paper fastener type but it is obvious that the disks might be connected by any

other suitable type of fastener desired according to the wishes of the person making these envelopes.

When producing this envelop the blank for the body portion is first stamped from cardboard or any other suitable material and the buttons are then put in place as shown clearly in Fig. 3. The string 24 is then tied to one of the buttons, preferably the end 60 button 17 around the pins thereof beneath the outer disks 22 of the button. The envelop is then ready for use and the photograph or other article which it is desired to send through the mail is placed in the 65 envelop and the address card 16 is then placed upon the envelop and the button moved to engagement with the same as shown in Fig. 1. When in this position the outer disks 22 of the various buttons overlap the edge portions of the address card and thus keep the address card in engagement with the envelop. The string is then passed around the buttons to overlap the 70 corner portions of the card until the string 75 has been returned to the button 17. The string will therefore not only serve to hold the buttons in tight engagement with the edge portions of the card but by overlapping the corner portions of the card will assist in holding the card in engagement with the envelop. If desired the string can be 80 twisted around each button to cause the string to be held in tight engagement with each button. After the string has returned to the button 17 and has been twisted about the pin of the same it is carried longitudinally around the envelop until it reaches the button 19. The string is now twisted 85 around the pin of this button 19 and is then carried to the button 20 from whence it is carried transversely around the envelop to 90 reach the button 18. After the string has been twisted around the button 18 the operation is completed and the envelop will be 95 securely held in a closed position although of course it may be readily opened by the proper authorities in order to permit the post office people to examine the contents of the package.

It will thus be seen that I have provided a mailing package or envelop which is provided with improved securing means simple in construction but very efficient in operation and serving the double function of holding the package in a closed condition and of releasably connecting an address card with

an envelop. It will also be seen that due to this construction the envelop can be retained by the person receiving the same through the mail and can be used again or may be 5 returned to the sender if the sender desires it returned.

What is claimed is:—

1. A mailing envelop having side and end flaps and being provided upon its back with 10 slots leading toward the edges thereof, engaging elements slidably mounted in the slots of said envelop, and a flexible securing element connected with one of said engaging elements and being passed around said 15 engaging element to connect the same and hold the engaging elements in a position to retain an address card in place and being then passed around the envelop and connected with said engaging elements to retain said 20 flaps in a closed position.

2. A mailing envelop provided with side and end flaps, engaging elements slidably connected with said envelop, and flexible

tying means connected with one of said elements and engaging the remaining elements. 25

3. A device of the character described comprising a body portion, engaging elements permanently connected with said body portion for sliding movement thereon, 30 and a securing element connected with one of said engaging elements.

4. A device of the character described including a body portion, securing means permanently connected with said body portion for sliding movement thereon, and means 35 for releasably holding said body portion in a closed position and holding said first mentioned securing means in a set position.

In testimony whereof I affix my signature 40 in presence of two witnesses.

OLIVER H. ORENDORFF.
